(57) **CLAIM**

The ornamental design for a measuring scale for a thermometer, as shown and described.

DESCRIPTION

FIG. 1 is a front view of a measuring scale for a thermometer, showing a first embodiment of my new design; and,

FIG. 2 is a front view of a measuring scale for a thermometer, showing a second embodiment of my new design.

The broken line showing in the drawing figures is for illustrative purposes only and forms no part of the claimed design.

1 Claim, 2 Drawing Sheets

FIG. 1

FIG. 2
